CLAIM

The ornamental design for an electric power storage module, as shown and described.

DESCRIPTION

FIG. 1 is a front elevation view of an electric power storage module showing our new design;

FIG. 2 is a rear elevational view thereof;

FIG. 3 is a right side elevational view thereof;

FIG. 4 is a left side elevational view thereof;

FIG. 5 is a top plan view thereof; and

FIG. 6 is a bottom plan view thereof;

FIG. 7 is a cross-section view taken along line 7-7 in FIG. 3;

FIG. 8 is a first perspective view thereof; and,

FIG. 9 is a second perspective view thereof.
